BOUNDARY NET FOR TENNIS COURTS AND
THE LIKE

Bernhard Panzer, Vienna, Austria

Application May 22, 1934, Serial No. 726,902
In Austria May 9, 1933

1 Claim. (Cl. 273—29)

This invention relates to detachable boundary nets for tennis courts and the like.

In prior detachable boundary nets, it has been the practice to provide specially cast uprights equipped with means for supporting the heavy and bulky sections of the net sections. The object of the present invention is to build up the whole boundary net structure out of standard parts, and in which the net sections may be

10 readily detached and attached.

Constructional examples of the invention illustrating the attachment of the net sections to the uprights and the anchoring of the uprights in the ground are shown in the accompanying drawing, in which:

Fig. 1 is an elevational view of the net according to the invention in which the means of attachment consist of hooks and eyes.

Fig. 2 is a plan view to be read in conjunction with Fig. 1.

Fig. 3 is a view in elevation of a net of which the sections are attached to the uprights by means of thumb-latches.

Fig. 4 is a plan view to be read in conjunction with Fig. 3.

Fig. 5 shows a net in which the individual sections are suspended by means of hooks from a round section iron rail or from a wire cable and steadied at the lower edge by being arranged

30 to ride by means of forks on a bottom rail or

cable of a similar nature.

Fig. 6 is an elevation taken at right angles to Fig. 5.

Fig. 7 is a plan view of a net adapted to be pressed against the uprights by means of springs.

In the form of construction shown in Fig. 1 there are attached to uprights *b* lugs *d* into which the sections of the net *a* are adapted to be hung by means of hooks *c*.

Fig. 3 shows a form of construction in which the individual sections *a* are adapted to be inserted between the uprights *b*, and to be pressed against the latter by means of pivoted thumb-latches *e*.

Fig. 5 shows a form of construction in which the individual sections *a* are suspended by means of hooks *g*. To the lower edge of the sections *a* there are fastened forks *h* adapted to engage the lower rod or cable and thereby to retain the sections in position.

Fig. 7 shows a form of construction in which the individual sections *a* are adapted to be inserted between the uprights *b*, and to be pressed against the latter by means of springs *i*. The fact that the sections of the net are detachable facilitates the treatment thereof with anti-rust agents or preparations.

I claim:

A boundary net for tennis courts, comprising spaced upright T-bars, an upper and a lower cable stretched between the flanges of adjacent T-bars, sections of netting bounded by a frame and of a size to fit between the adjacent T-bars and hooks engaged in the frame of the sections and in the upper and lower cables to hold the sections in position.

BERNHARD PANZER. 35
